UNITED STATES PATENT OFFICE.

CHARLES FRANCIS RICHARDSON, OF WOONSOCKET, RHODE ISLAND, ASSIGNOR TO
JAMES A. WHITCOMB, OF NEW YORK, N. Y.

TYPE-WRITING MACHINE.

1,126,278.

Specification of Letters Patent.

Patented Jan. 26, 1915.

Application filed September 20, 1910. Serial No. 582,891.

To all whom it may concern:

Be it known that I, CHARLES F. RICHARDSON, a citizen of the United States, and a resident of Woonsocket, county of Providence, State of Rhode Island, have invented 5 certain new and useful Improvements in Type-Writing Machines, of which the following is a specification.

This invention relates broadly to improvements in typewriting machines and 10 specifically to type rests particularly adapted for machines known as bar typewriters.

The principal object of this invention is to construct a type bar rest having a greater 15 radius of curvature than the radius of curvature of the segment upon which the type bars are mounted.

Another object of this invention is to provide 20 a type bar rest of such construction that the type bars near the center of the rest move through a smaller segment of an arc in moving from their position of rest on the type bar to the printing point, than that through which the bars located at the extremity of the rest move.

Another object of this invention is to construct 25 a type bar rest in such manner that the bridge portion, the backing and the rest proper may be all formed from a single sheet of metal.

Another object of this invention is to construct 30 a combined type bar rest and key lever spring supporting bridge.

Still other and further objects of this invention will, in part be obvious and will in 35 part be pointed out in the specification which follows hereinafter, by reference to the drawings in which like numerals are used to indicate like parts throughout the several figures, and the scope of the invention 40 will be indicated by the appended claims.

Figure 1 is a view showing a portion of 45 the typewriting machine in sectional elevation. Fig. 2 is a view showing the rear of a typewriting machine in elevation, and illustrating the difference in curvature between the type bar hanger segment and the type bar rest. Fig. 3 is a front perspective view of the type bar rest. Fig. 4 is a rear perspective view of the type bar rest.

Referring particularly to the drawings, a type bar rest 1 is attached to the sides 2 and 4, by means of screws 5 and 6, which pass through openings 7 and 8 in bracket portions 9 and 10 of the type bar rest, and are screwed into the side frames 2 and 4, in such manner that the type bar rest 1, becomes a bracing member across the upper part of the machine frame to maintain the side 60 frames 2 and 4, in rigid relationship. This feature is of considerable importance for the reason that the machine frame 3, is made of a single piece of sheet metal in the form of an open shaped U, having the open portions 65 thereof toward the front. Key levers 11, 12 and 14, are pivotally mounted upon key lever pivot rods 15, 16 and 17 respectively, which are also fixedly mounted in the sides 2 and 4 of the machine frame 3. The key levers 15, 70 16 and 17, are provided at their front portions with finger caps 18, 19 and 20 respectively, and at their rear ends are provided with connecting eyes 21. Type bar hangers 22, are mounted upon a segment 24, 75 that is formed in the rear wall of the machine frame 3. Type bars 25 are pivotally mounted in the type bar hangers 22, and are connected to the connecting eyes 21, carried by the key levers, by means of links 26. 80 The type bars are provided on their forward ends with type heads 27, that are adapted to rest upon a resilient pad 28, that is carried by the lower curved wall 29 of the type bar rest 1. Key lever returning 85 springs 30, 31 and 32, are adapted to be suspended from a bridge portion 34, of the type bar rest 1, by engaging loops which pass through openings 35 at the rear end of the bridge portion 34, and are attached at their 90 lower ends to the key levers 11, 12 and 14 respectively. A front board 36, is mounted between the side walls 2 and 4 of the machine frame, and is adapted to substantially cover and protect the key lever springs 30, 95 31 and 32.

Referring particularly to Fig. 2 of the drawings, it will be noted that the radius of curvature of the type bar hanger segment 24, is considerably shorter than the radius 100 of curvature upon which the curved wall 29 of the type bar rest is formed. Since the

type bars 25, when at rest, are supported on their rear ends in the hangers 22, and rest at their forward ends upon the resilient pad 28, carried by the curved wall 29 of the type bar 5 rest, it will be noted that the type head on the middle type bar will travel a shorter segment of an arc from its position to rest on the pad to the printing point on the platen, than the segment of arc which will be traveled by the type head on the type bar mounted 10 in a hanger located at the extremity of the type bar segment. It will also be seen that the angle formed between the printing point, the pivot of the type bar and the type 15 upon the type bar head, considering the pivot of the type bar an apex of the angle, will be more acute for the type bars mounted at the middle of the segment, than for the type bars mounted at the extremities of 20 the segment when the type bars are in their position of rest upon the type bar rest. This relationship of the difference in length of radii between the type bar segment and the type bar rest, enables the type at the extremity of the type bar segment to "fan out" at their type carrying ends, and therefore the type bars are separated a greater distance at their forward ends than at their rear ends when the type bars are in normal 25 position on the type bar rest. This is of great advantage in gaining space between the type heads for the outer bars, for the reason that the type bars at the outer ends of the segment are bent at a considerable angle 30 to the body of the bar and are apt to interfere with each other when dropping back to normal position on the type bar rest.

Referring particularly to the type bar rest *1 per se*, it comprises a single piece of 40 sheet metal formed with bracket portions 9 and 10, between which extends a bridge portion 34, which is perforated with a series of holes or openings 35, in order to support the key lever springs, as has been hereinbefore 45 described. The type rest curved wall 29, is formed by drawing down a portion of the front edge of the type bar rest into the proper and desired curve, in such manner as to leave a back supporting wall 37, between 50 the bridge portion 34 and the curved wall 29. This particular construction forms an extremely simple, and at the same time, rigid type bar rest which is particularly adapted to typewriting machines of the folding type 55 wherein simplicity of parts and lightness in comparison to strength is of the greatest importance.

Having thus described my invention what I desire to claim is:—

60 1. In a typewriting machine, the combination of a machine frame, a type bar hanger segment attached to said machine

frame, type bars mounted upon said type bar hanger segment, means for actuating said type bars, and a type rest mounted in 65 said machine frame, the radius of curvature of said type rest being greater than the radius of curvature of the type bar hanger segment, said type rest and said segment being so related that a horizontal projection 70 of their curves intersect, substantially as described.

2. In a typewriting machine, the combination of a machine frame, a type bar hanger segment attached to said machine 75 frame, type bars pivotally mounted upon said type bar segment, key levers pivotally mounted in said machine frame and operatively connected with said type bars, a type bar rest having a straight bridge portion 80 and a curved type bar supporting segment, and key lever returning springs attached to said type bar rest and to said key levers.

3. In a typewriting machine, the combination of a machine frame, a type bar hanger segment attached to said machine frame, type bars pivoted upon said type bar hanger segment, key levers pivotally mounted in 85 said machine frame, and operatively connected with said type bars, a type rest being 90 formed upon a segment of a vertical arc of greater radius than the radius of the type bar hanger segment, the centers for said radii being in different horizontal lines, and returning springs attached to said type bar 95 rest and to said key levers, substantially as described.

4. In a typewriting machine, the combination of a U-shaped frame formed from a single sheet of metal, a type bar rest mounted in said machine frame near the upper middle portion thereof, and constructed in such manner as to form a brace between the walls of said machine frame, and a front board substantially covering said type bar 100 rest, substantially as described.

5. As a new article of manufacture, a combined brace and type bar rest and key lever returning spring support, said device comprising a substantially horizontal spring 105 support and a curved type bar rest for trussing and stiffening said spring support, substantially as described.

6. As a new article of manufacture, a brace including a type bar rest, and a key lever returning spring support formed integral from a single sheet of metal, said spring support being a substantially horizontal flat plate stiffened by the curved type 110 bar rest, said plate and said rest being connected throughout their respective lengths, substantially as described.

7. As a new article of manufacture, a type bar rest formed with a straight bridge

portion and a curved type bar supporting segment, substantially as described.

8. As a new article of manufacture, a type bar rest formed from a single sheet of metal and constructed with a straight bridge portion, a curved type bar supporting member, and a backing wall between said curved sup-

porting member and said bridge portion, substantially as described.

CHARLES FRANCIS RICHARDSON.
